Application September 6, 1950, Serial No. 183,439

3 Claims. (Cl. 179—171)

1

The present invention relates generally to amplifier circuits. More specifically, the present invention relates to control circuits for parallel connected amplifier tubes wherein both a variable D. C. bias voltage and a signal potential are applied to each amplifier grid element.

Tube manufacturers usually keep up with the industrial need for tubes having a large current rating. However since consumer need always precedes ultimate production, industry has found it necessary to electronically control blocks of current which are too heavy for any single available tube. When this problem arises, the only design "out" is to use a parallel bank, so that the large load current can be divided. The use of a plurality of tubes to divide the total load current, though solving the problem of keeping plate current flow in each tube below maximum safe operating limits, involves a new problem of controlling the plate current excursions in the various tubes. It is with this latter problem that we are concerned here.

Slight variations in amplifying characteristics among tubes having identical manufacturers ratings obviously cause variations in the plate current excursion rates. Though a slight difference in the rate of plate current change is not too important in most installations, any sizeable difference as well as any difference in the maximum plate current drawn by different tubes in the parallel bank is objectionable.

The problem has been met by prior art teachings through use of an individual bias control for each parallel connected tube in addition to an individual input signal amplitude control for each tube. By this means, the operating point on the characteristic curve for each tube is separately selected and also the amplitude of the input signal, or the signal swing around the chosen operating point, is also separately selected. Though the prior art circuits have merit in that a plurality of tubes may be operated in parallel, a simplified control system would be desirable for use where a parallel bank must include three or more tubes.

Where tubes are operated in parallel in a conventional circuit, the operator is forced to dynamically balance the load current by applying a signal or "tone" frequency as well as apply the correct bias voltage to balance the "idle" current flow or the plate current flowing in the absence of a grid signal. Usually the input signal transformer secondary has a large number of taps one of which must be selected to effect a dynamic balance. Especially is this true when three or more

2

tubes are involved, making the problem of load division rather complex and making the maintenance problem very difficult.

It therefore becomes a general object of my invention to simplify the amplifier control network in a parallel bank type of circuit.

A second factor, that is involved in the need for the present invention, arises primarily because of the high cost of kilowatt rated amplifier tubes. Lack of demand causes tubes of this size to be predominantly handmade or at least produced with a minimum of mass production tooling up and a maximum of labor. Thus a high production cost. Also, tubes of this size are usually rejected if there is any appreciable difference between their amplifying characteristic and the amplifying characteristic of the selected "norm" and of course the cost of rejects must be added to the cost of the tubes having acceptable characteristics. Thus it would be desirable to devise a circuit wherein these "rejects" can be operated in parallel with tubes having correct normal characteristics.

Therefore, a primary object of my invention is to devise a simplified control means capable of controlling a parallel connected amplifier bank in which tubes having slightly different plate current characteristics can operate side by side, each carrying its proportionate share of load current.

A still further basic object of the present invention is to provide a unitary means for controlling the plate current excursion of each tube in a parallel connected amplifier bank.

In the illustrated embodiment of my invention, I choose to show a push-pull type of amplifier using three or more tubes in parallel on each side. The secondary of the input transformer has a bias source connected thereto along with a single potentiometer for each tube in the parallel bank. By connecting the potentiometers in parallel so that the same bias voltage and the same signal is impressed across each potentiometer I make it possible to control the bias and signal voltage amplitude for each tube with a single unit. After adjusting the variable arms on the potentiometers which are connected to the grid of each tube, so that the "idle" current, that is the current drawn by each tube in the absence of a signal is the same, I find that there is always an equal division of plate current flow among the tubes when a signal is impressed upon the circuit. In other words, I have found that there is a linear relationship between the signal amplitude and bias voltage required to maintain similar plate current excursions in the various parallel con-

nnected tubes. For a better understanding of the present invention, together with other and further objects, advantages and capabilities thereof reference is made to the following disclosure and appended claims in connection with the accompanying drawings, in which:

Fig. 1 is a circuit diagram illustrating the teaching of the prior art;

Fig. 2 is a circuit diagram showing the invention used in a push-pull amplifier stage; and

Figs. 3 and 4 are curves illustrating the operation of the control systems shown in Figs. 1 and 2.

In Fig. 1, I have shown a typical prior art class B operated push-pull type of amplifier which uses three tubes in parallel on each side of the circuit to modulate a 200 kw. transmitter. An A. C. signal can be assumed to be taken from the secondary of transformer 10, which has a center tap to ground, dividing the secondary into two parts. Also, I have shown a plurality of taps, e. g. 2% taps, connected to each half of the divided secondary. Of course in actual practice it is not uncommon to use as many as 10 taps on each side of the divided secondary, however, operation of the circuit of Fig. 1 can be adequately explained using only the three taps which I have shown. Each tap on the transformer is connected to a terminal on a plurality of switching device such as units 11, 12 and 13. The variable arm on each switching device is connected via a blocking condenser coupling to the grid of an amplifier tube. For example, switch arm 14, of device 11, is connected through condenser 15 to grid 16 of tube 17. Also, switch arm 18, of switch device 12, is connected through condenser 19 to grid 20 of tube 21. It can be seen that tubes 22, 23, 24 and 25 are similarly connected to the secondary of transformer 10. By adjusting the switch arm in the appropriate switching device, the operator can select the desired amplitude of input signal impressed across the grid of each tube.

In order to keep the signal voltage from being dissipated in the low impedance bias source, a resistor, such as resistance 30, 31 and 32, is connected between the grid of each tube and the variable arm on the appropriate potentiometer. These resistors having a very high value, keep the bias source from loading the signal source.

In operating the circuit before the signal can be applied, the operator must first adjust the bias voltage so as to select the correct operating point, i. e. "idle" current, for each tube. For purposes of explaining how the correct bias voltage is selected, reference will be made to the curves shown in Fig. 3. Though this set of curves as well as the curves shown in Fig. 4 are not exact duplicates of any actual characteristic curves, they are adequate for the purpose of explaining circuit operation. In Fig. 3 is shown a conventional e_g/i_p set of coordinates with e_g plotted on the abscissa and i_p plotted on the ordinate. If it be assumed that the e_g/i_p characteristic of tube 21 in Fig. 1 can be shown by a curve similar to curve 70, and that curve 71 illustrates the e_g/i_p characteristic of tube 22, it can be shown that different bias potentials must be applied to the grid circuits of these two tubes in order to cause identical "idle" current flow.

If both tubes have a control circuit bias potential impressed which is equal in magnitude to point 0 on curve 70, a vertical projection of point 0 which intersects curve 71 indicates the idle current which would flow in the tube of

curve 71. It will be seen that the idle current in the tube of curve 70 is low and equal to i_{p1} , while the idle current in the tube of curve 71 is high and equal to i_{p0} . It now becomes obvious that two tubes having different amplifying characteristics can not be operated in parallel so as to have equal idle current flow, unless a different bias potential is applied to each grid circuit. In actual practice, the correct grid bias is chosen by placing a meter in each cathode circuit and adjusting the bias voltage until all meters show that the selected and the same idle current is flowing in each tube. In our case this would be i_{p1} as shown in Fig. 3.

After the operator balances the idle current flow in the various parallel connected tubes, then the circuit must be dynamically balanced, or balanced for operation under signal conditions. A dynamic balance is reached by using a cut-and-try process to select the correct 2% taps while a signal or tone source is driving the grids through the input transformer.

This cut-and-try process requires two adjustments for each tube and when a plurality of tubes are operated in parallel the operation is somewhat tedious unless a very large number of taps are supplied on the input transformer secondary. Experience has shown that the maintenance problem grows by leaps and bounds with each increase in the number of take-off taps used.

In Fig. 2 I have illustrated an embodiment of my invention using a push-pull type amplifier, preferably operated in class B. Again I have used three tubes in parallel on each side of the push-pull circuit. As the explanation unwinds it will become obvious that this simplified control system is equally applicable to circuits using more or less than three tubes in parallel as well as to circuits other than those of the push-pull type.

A signal is developed across the secondary of the transformer which has a center tap connected to a negative source of bias potential. The remaining two terminals of the transformer secondary are each connected to one side of different banks of parallel connected potentiometers. One bank, or the top illustrated bank, is composed of potentiometers 41, 42 and 43 all connected in parallel. The other bank, or the lower illustrated bank of potentiometers, comprises potentiometers 44, 45 and 46. The other terminal of the upper illustrated bank is connected to ground through resistance 47 while the other terminal of the lower bank of potentiometers is connected to ground through resistance 48. It can be seen that the source of negative bias potential which is connected between the secondary of transformer 40 and ground will cause a current flow through resistance 47, the upper illustrated potentiometer bank, including potentiometers 41, 42 and 43, and one half of the secondary of transformer 40. This bias source will also cause current flow from ground through resistance 48, the lower illustrated potentiometer bank and the remaining half of the secondary of transformer 40. Resistors 47 and 48 have equal resistance values, and the resistance of each potentiometer bank is also identical. Because of this circuit symmetry, there are two D. C. currents flowing in the secondary of transformer 40 in opposite directions, each in a separate half of the winding thereby inducing an equal and opposite flux in the transformer core. Since the flux set up by one current bucks the

5

flux set up by the other current, as far as the transformer secondary is concerned, it is the same as if no current flowed through it from the bias source. In other words, this type of symmetrical connection avoids D. C. saturation.

The variable arm on each potentiometer is connected to the grid of a separate tube. For example, the upper potentiometer bank, which is used to control tubes 49, 50 and 51 has three variable potentiometer arms. Potentiometer arm 54 of potentiometer 42 is connected to grid 55 of tube 50. Also potentiometer arm 56 of potentiometer 41 is connected to grid 57 of tube 51. Similar symmetrical connections are made between the lower potentiometer bank and the grids of tubes 58, 59 and 60.

In order to understand how my novel circuit operates reference should again be made to Fig. 3, where I have shown two signals having equal amplitudes, each one swinging about the operating point on a different tube characteristic. Signal curve 72 is shown as swinging around the operating point on curve 71, which in this case represents the characteristics of tube 50. Dotted curve 73, having the same magnitude as wave 72 is shown swinging around the operating point on curve 70, which represents the characteristics of tube 49. Projecting the peaks of curve 72 and 73 upon the appropriate characteristic curve it can be seen that these two signals cause different peak plate current flow in the two tubes. A signal having the amplitude of curve 73 would cause tube 49 to draw a peak plate current equal to i_{p49} , a value which is much higher than i_{p50} , the current which a signal of equal amplitude draws in tube 50. Since we must have equal plate current flow in the two tubes, it becomes necessary to reduce the amplitude of the signal swing impressed across the grid circuit of tube 49. Curve 74 represents the reduced amplitude of input signal swing. Vertically projecting the peak of curve 74 so that it intersects curve 70 shows that a reduced signal amplitude can be selected which makes the plate current flow in tube 49 equal to i_{p50} the current flowing in tube 50.

Though this principle, of load division by reducing the signal swing in some of the parallel connected tubes, was well known in the prior art, no one seemed to realize that there was a relationship between the percentage change in the signal amplitude and the percentage change in the necessary bias voltage magnitude. I have found that there is such a relationship between these voltages of which advantage can be taken to eliminate the old cut-and-try adjustment process along with many circuit elements formerly deemed necessary.

To state the relationship, if tube 50 is considered as the "norm" and the bias voltage applied to its grid circuit is considered to be the standard, the percentage reduction of the "normal" bias voltage value which, when impressed on the grid circuit of tube 49, is necessary to cause the same idle current to flow in the higher mu tube 49, is equal to the percentage by which the amplitude of the input signal fed to tube 50 must be reduced when fed to tube 49 in order to make tube 49 draw the same maximum plate current as tube 50 on the peak of the input signal. This is a linear relationship. For example, if it becomes necessary to have a 10% lower grid bias on the grid of tube 49 than that impressed on the grid of tube 50, in order to equalize idle currents, it is also necessary to have a signal im-

6

pressed upon the grid of tube 49 which is 10% lower in peak magnitude than the signal impressed upon the grid of tube 50. Thus, if it be assumed that the difference (d), as shown in Fig. 3, between the bias voltages supplied to tubes 49 and 50 is equal to 10% of the bias voltage supplied to tube 50, then the difference (f) between the amplitudes of the input signals fed to these two tubes will also be equal to 10% of the amplitude (g) of the signal fed to tube 50.

To show how I use this ratio in my novel circuit for purposes of simplification, it will be remembered that each potentiometer in the parallel potentiometer bank of Fig. 2 has the same bias voltage impressed across it as is impressed across the remainder of the potentiometers. It will also be remembered that each potentiometer has the same magnitude of input signal impressed across it as is impressed across the remainder of the potentiometers in the potentiometer bank. Thus, when any potentiometer arm is adjusted, for example, potentiometer arm 56 of potentiometer 41, both the bias voltage and the input signal are linearly adjusted in the same polarity direction by equal percentages. In other words, when the contact on potentiometer arm 56 is moved toward ground, the bias voltage and the amplitude of the input signal fed to grid 57 of tube 51 are reduced by the same percentage. This means that, if the contact is dropped or moved toward ground to a point which reduces the grid bias voltage say 10% for example, the amplitude of the input signal fed to grid 57 is also reduced 10%.

Another way of looking at this is shown by the curves illustrated in Fig. 4. Again the characteristic curves of two tubes are shown; however, it must be realized that the principle involved applies equally as well to the relationship between the input signal and operating bias applied to all of the tubes. The higher mu tube which could be tube 49 can be assumed to have a characteristic such as that shown by curve 80, while the lower mu tube which could be tube 50 has a characteristic curve similar to curve 81.

When the bias voltage is adjusted on each tube so as to make point (O) the operating point, each tube will draw an idle current having a magnitude equal to i_{p1} . In order to better illustrate the comparison between the input signal amplitudes which should be applied to each tube I have included a dotted version of curve 80 shifted over so that the operating point of this curve intersects the operating point on curve 81. Now, assuming that the input signal of both of these tubes swings around this single operating point, the correct amplitude of input signal for each tube can be plotted. If the input signal for tube 50 has an amplitude similar to the amplitude of curve 82 then plate current will be drawn by this tube equal to i_{p50} . In order to draw the same plate current in tube 49 at the peak of the input signal, a signal having a peak amplitude similar to curve 83 must be impressed upon the grid circuit of tube 49. The difference in amplitude between these two signals is again indicated by the letter f. The amplitude of signal 82 is again indicated by the letter g. The necessary bias for tube 50 is again shown as e_g and the difference in bias required for tube 50 and tube 49 is again shown by the letter d. I have found that the relationship $f/g = d/e_g$ holds true for the majority of tubes which are usually rejected.

After this rather exhaustive explanation, it

can be seen that the unitary control device with which I control both the bias voltage amplitude and the signal voltage amplitude for each tube in the parallel bank is capable of producing, in fact necessarily produces, the above mentioned ratios. Therefore, with this simple control device I am able to divide a load current equally between the various tubes without the complexity of the cut-and-try process necessary in the prior art circuit shown in Fig. 1. All the operator has to do, in my novel circuit, is to adjust the potentiometer for each tube so that the same idle current is drawn by all of the tubes and then apply a signal to the circuit. There is no cut-and-try process involved, because once the idle current is set, the circuit is automatically adjusted to dynamically divide the load current under signal conditions.

While I do not desire to be limited to any specific circuit parameters, such parameters varying in accordance with individual designs, the following circuit values have been found entirely satisfactory in one successful embodiment of the invention, in accordance with Fig. 2:

Potentiometers 44-45	300 ohms
Resistance 47, 48	3875 ohms
Tubes 49, 50, 51, 55, 59, 60.	Federal 9628 or 125A
Bias source (-6)	3500 volts
B+	12,000 volts

While there has been shown and described what is at present considered the preferred embodiment of the present invention, it will be obvious to those skilled in the art that various changes and modifications may be made therein without departing from the invention as defined by the appended claims.

Having thus described my invention, I claim:

1. In an amplifier the combination comprising a plurality of tubes having e_g/i_p characteristics such that substantially the same ratio exists in each tube between the bias potential and the peak signal potential necessary to cause a given plate current to flow, each tube having at least an anode, a cathode and a control grid, means connecting the anodes of said tubes directly in parallel, means connecting the cathodes of said tubes to a common equipotential plane, an output circuit coupled between said parallel connected anodes and said equipotential plane, a first terminal and a second terminal, said second terminal being D.-C. coupled to said equipotential plane, a separately associated potentiometer for each tube, each potentiometer having a resistor element connected between said first and said second terminals and a resistor-element variable contact arm, means for D.-C. coupling the control grid of each of said tubes to its associated potentiometer variable contact arm, a source of signal voltage coupled across said first and second terminals, and a source of bias voltage having a positive terminal D.-C. coupled to said second terminal and a negative terminal D.-C. coupled to said first terminal, whereby the amplifiers are adjusted for dynamic load current division by adjusting the potentiometers so as to balance the idle current among the tubes.

2. In an amplifier of the balanced parallel tube type, the combination comprising a first terminal and a second terminal, a plurality of potentiometers each having a resistance element connected between said first and second terminals and each having a variable contact, a source of signal voltage coupled between said first and second terminals, a source of bias voltage having a negative terminal D.-C. coupled to said first terminal and a positive terminal D.-C. coupled to said second terminal, a plurality of amplifier tubes each having e_g/i_p characteristics such that substantially the same ratio exists in each tube between the bias potential and the peak signal potential necessary to cause a given plate current to flow and each tube having at least a control grid, an anode, and a cathode, each of said tubes being associated with a separate potentiometer, said anodes being connected to a first common point and said cathodes being connected to a second common point, a source of anode potential and a load means series coupled between said first and said second common points, means for D.-C. coupling each one of said plurality of control grids to the associated potentiometer variable contact and means for coupling said second terminal to said common cathode point, whereby the amplifier tubes are adjusted for dynamic load current division by adjusting the potentiometers so as to balance the idle current among the tubes.

3. In an amplifier of the balanced parallel tube type the combination comprising a first terminal and a second terminal, potentiometer means connected between said first and second terminals having a plurality of variable contact arms, a source of signal voltage coupled across said first and second terminals, a source of bias voltage having a negative terminal D.-C. coupled to said first terminal and a positive terminal D.-C. coupled to said second terminal, a plurality of amplifier tubes each having e_g/i_p characteristics such that substantially the same ratio exists in each tube between the bias potential and the peak signal potential necessary to cause a given plate current to flow and each having at least a control grid, an anode, and a cathode, each of said control grids being connected to a separate variable contact arm on said potentiometer means, circuit means connecting said anodes and cathodes in parallel tube relationship, and means D.-C. coupling said second terminal to said cathodes, whereby the amplifiers are adjusted for dynamic load current division by adjusting the potentiometer contacts so as to balance the no-signal idle current among the tubes.
